PHOTOGRAPHIC LAMP UNIT

James T. Aneshansley, Brooklyn, N.Y., assignor to
American Speedlight Corporation, New York, N.Y.

Filed June 25, 1962, Ser. No. 70,675

Term of patent 14 years

(Cl. D61—1)

FIGURE 1 is a perspective view of a photographic lamp unit showing my new design, with the support omitted for ease of illustration.

FIGURE 2 is a side elevation thereof with the support fragmentarily shown.

FIGURE 3 is a front elevation thereof, with a bulb shown in dotted lines for illustrative purposes only.

FIGURE 4 is a rear elevation thereof.

FIGURE 5 is a sectional view looking in direction of arrows 5—5 in FIG. 2.

The dominant features of my design reside in the portions shown in full lines, which portions are characterized by the specific configuration of the handle member in combination with the reflector housing as shown.

I claim:

The ornamental design for photographic lamp unit, as shown and described.
